CARRIER FOR VACUUM CLEANER TOOLS

Dewey M. Dow, Toledo, Ohio, assignor to Air-Way Electric Appliance Corporation, Toledo, Ohio, a corporation of Delaware

Application January 5, 1954, Serial No. 28,382

Term of patent 7 years

(Cl. D58—26)

To all whom it may concern:

Be it known that I, Dewey M. Dow, a citizen of the United States and a resident of Toledo, Lucas County, Ohio, have invented a new, original, and ornamental Design for a Carrier for Vacuum Cleaner Tools, of which the following is a specification, reference being had to the accompanying drawing forming a part thereof.

In the drawing:

Figure 1 is a rear perspective view of a carrier for vacuum cleaner tools showing my new design;

Figure 2 is a top plan view of the carrier with the handle removed for convenience of illustration; and

Figure 3 is a side elevational view thereof taken from the left side with parts broken away for convenience of illustration.

The front and side of the carrier not shown are the same as those shown.

I claim:

The ornamental design for a carrier for vacuum cleaner tools, as shown and described.
